(57) **CLAIM**

The ornamental design for a fold-out screen portion for a mobile phone, as shown and described.

DESCRIPTION

FIG. 1 is a perspective view of fold-out screen portion for a mobile phone.

FIG. 2 is a front view of FIG. 1.

FIG. 3 is a rear view of FIG. 1.

FIG. 4 is a left side view of FIG. 1.

FIG. 5 is a right side view of FIG. 1.

FIG. 6 is a top view of FIG. 1.

FIG. 7 is a bottom view of FIG. 1.

FIG. 8 is a front view of the invention of FIG. 1 in a partially unfolded state.

FIG. 9 is a perspective view of the invention of FIG. 1 in a wholly folded state.

FIG. 10 is a front view of FIG. 9.

FIG. 11 is a rear view of FIG. 9.

FIG. 12 is a left side view of FIG. 9.

FIG. 13 is a right side view of FIG. 9.

FIG. 14 is a top view of FIG. 9; and,

FIG. 15 is a bottom view of FIG. 9.

The broken line showing of environmental structures is for illustrative purposes only and forms no part of the claimed design.
